UNITED STATES PATENT OFFICE

2,438,725

DENTAL INLAY

Abraham H. Tamarin, Chicago, Ill.

Application April 30, 1945, Serial No. 590,996

2 Claims. (Cl. 32—12)

1

The invention relates to dental inlays made of any suitable material such as precious metal or plastic material and to the method of securing the inlay against dislodgement.

The securing of inlays has always formed a difficult problem and many attempts were made to prevent the dislodgement and loss of inlays.

The employment of pins or posts and the use of special cements have contributed little, if anything, in permanently securing an inlay.

It is, therefore, one of the main objects of the invention to provide an inlay which is permanently secured to a tooth and is retained in such position for the life of a tooth, so that the inlays may be used as an abutment for bridgework.

Another object constitutes the provision of an anchor which is embedded in the tooth and formed integral with the inlay so that the adhesive effect of a cement is only partly relied upon to secure the inlay against dislodgement.

With these and other important objects in view which will become apparent from a perusal of the invention, the latter comprises the means and the method of applying the means set forth in the specification, particularly pointed out in the claims forming a part thereof, and illustrated in the accompanying drawing, in which

Fig. 1 is a perspective view of an anchor constructed in accordance with my invention.

Fig. 2 is a cross section through a tooth in the process of applying my improved inlay.

Fig. 3 is a top plan view of a tooth provided with an inlay.

Fig. 4 is a section similar to Fig. 2 with the improved inlay applied.

Figs. 5 to 7 are elevational views of drilling and burring tools employed in carrying out my invention, and

Fig. 8 is a perspective view showing an inlay to be applied to a tooth.

The invention may be applied to distooclusal as well as mesiooclusal inlays and broadly provides an anchor which protrudes from the inlay and is received in an auxiliary cavity where a body of cement is trapped which holds the anchor and prevents loosening or dislodgement of the inlay.

Referring to the drawing 10 generally designates a tooth which has a cavity 11 to which an inlay is to be applied.

As shown in Figs. 2 and 4 the tooth is provided with a hole 12 which at the lower part is widened as at 13 designing a chamber and producing shoulders 14.

The hole 12 is provided to receive an anchor

2

generally designated by 15 and comprising a cylinder 16 from which extend at the longitudinal center pins 17 and 18 terminating in a head 19 and 20 respectively.

Attention is called to the fact that the cylinder and the headed pins each are 1 mm. long so that the total length of the anchor pass does not exceed 3 mm.

These dimensions have been found practical and are given merely by way of example and not as a limitation.

The cylinder is formed with a longitudinal groove 21 and the heads 19 and 20 each have a marginal groove or peripheral recess 22 for a purpose hereinafter to be referred to.

In carrying out the invention the tooth is provided with the auxiliary hole 12 which is formed with a drill 23 having a shoulder forming an abutment to prevent excessive penetration of the drill into the tooth.

The operative part 25 of the drill has substantially two-thirds of the length of the anchor post and upon insertion of the anchor post into the hole, the pin 18 and its head extend into the cavity 11.

A bur 26 is employed which also has a shoulder 27 to prevent excessive penetration for dressing the bottom of the hole 12. Finally a bur 28 having a thin stem 29 enables the diameter 30 of the lower part of the hole 12 to be increased whereby shoulders 14 are formed.

Thereupon the anchor post is inserted in the hole 12 so that the top surface of the cylinder 16 is flush with the bottom of cavity 12. The cylinder 16 serves as a guide means when inserting the post.

Thereupon wax is pressed into the tooth whereby the head 20 and pin 18 become embedded in the wax.

Upon removal of the wax pattern the anchor post is carried along and the inlay 30 cast, resulting in an integral structure of inlay and anchor post 15.

The cavity and the functional inlay surfaces as well as the anchor post are covered with cement. In mounting the inlay excessive cement may escape through the grooves 21, 22.

Upon hardening the cement in chamber 13 forms a block 31 connected by the post 15 with the inlay 30 and bearing against shoulders 14 extending at right angles to the post 15 to effectively prevent any dislodgement or loosening of the inlay.

The inlay shown in Fig. 8 has two anchor posts 15 if double anchorage is desired.

The inlay thus secured may serve as an abutment for bridgework with the same assurance of retention and security as a crowned tooth, since the block of cement trapped in the chamber 13 forms a rigid assembly, with the post and inlay.

Attention is called to the fact that the anchor may be employed for distoocclusal or mesioclusal inlays regardless of ease or difficulty of access to the cavity.

While the drawing discloses one embodiment of the invention numerous changes and alterations may be made without departing from the spirit of the invention. I, therefore, do not limit myself to details of construction or arrangement of parts as shown, but claim my invention as broadly as the state of the art permits.

I claim:

1. A dental anchor comprising a cylindrical portion formed with pins longitudinally extending from the center thereof, and provided with heads at the free end, said cylindrical portion and heads being provided with a peripheral groove parallel to the longitudinal axis to provide a channel.

2. For use with an inlay of precious or semi-

5

10

precious metal to be applied to a tooth in situ, a dental anchor comprising a cylindrical portion formed with pins longitudinally extending from the center thereof, and provided with heads at the free end, said cylindrical portion and heads being provided with a peripheral groove parallel to the longitudinal axis to provide a channel, said anchor being adapted to be cast to said inlay affording the securing of said inlay

and said anchor as a unit to the tooth.

ABRAHAM H. TAMARIN.
